AQUARIUM LIGHT FIXTURE

Andrew S. Dribnack, Binghamton, N. Y.

Application April 18, 1952, Serial No. 19,391

Term of patent 14 years

(Cl. D48—20)

To all whom it may concern:

Be it known that I, Andrew S. Dribnack, a citizen of the United States of America, residing at Binghamton, in the county of Broome and State of New York, have invented a new, original, and ornamental Design for Aquarium Light Fixture, of which the following is a specification, reference being had to the accompanying drawing, forming part hereof, in which:

Figure 1 is a side elevational view of an aquarium light fixture, embodying my new design;

Fig. 2 is a front elevational view of the fixture of Fig. 1; and

Fig. 3 is a top plan view.

I claim:

The ornamental design for an aquarium light fixture, substantially as shown.

ANDREW S. DRIBNACK.
